CUTTING TOOL

William T. Bradley, St. Louis, Mich.

Application August 9, 1943, Serial No. 497,948

8 Claims. (Cl. 30—329)

This invention relates to cutting tools and more particularly to those especially adapted for cutting and grooving fibrous materials, such as composition board.

The principal object of the invention is to provide a convenient tool of the character described adapted to hold any one of a number of interchangeable unitary blade holders for making different types of cuts in composition boards and the like.

Another object of the invention is to provide such a tool of extremely simple and economical construction.

A still further object is to provide a novel form of latch for releasably holding any one of a number of unitary blade holders in the cutting tool whereby the different blade holders may be quickly interchanged with each other.

A still further object is to provide a tool of the character described in which a blade holder is firmly located against movement relative to the main body of the cutting tool.

These objects will more fully appear in the following specification when read in connection with the accompanying drawings, wherein—

Figure 1 is a side elevational view of the main body of the tool, parts being broken away to more clearly show the construction thereof;

Figure 2 is a bottom plan view of the main body of the tool with parts broken away to show the interior construction thereof;

Figure 3 is a top plan view of one of the interchangeable blade holders employed with the tool;

Figure 4 is a side elevational view of the blade holder shown in Figure 3;

Figure 5 is a side elevational view of the complete tool with the blade holder of Figures 3 and 4 in place therein;

Figure 6 is a cross-sectional view taken on substantially the line 6—6 of Figure 5; and

Figures 7 and 8 are side elevational and bottom plan views respectively of another type of blade holder for use with the tool.

Referring now to the drawings in more detail, the invention comprises generally a main body portion 10, releasable latching means designated in its entirety by the numeral 11, and a releasable blade holder, such as that shown in Figures 3 and 4 or in Figures 7 and 8.

The main body portion 10 of the tool is an elongated block of generally rectangular cross-section having a flat bottom work engaging surface 12. The body portion 10 may be of any suitable material, but preferably it is formed of wood or molded plastic material. Between the ends of the block and extending upwardly from the bottom surface thereof is a recess 13. The recess extends from side to side of the block, and is of generally rectangular configuration. At one side of the recess is a V-shaped groove 14 which extends from the bottom surface 12 to the top of

the recess 13. The upright corners of the recess 13 on one side thereof are beveled to provide shoulders 15, the purpose of which will presently appear.

A cylindrical hole 16 extends from the end of the block opposite the groove 14 through the adjacent wall of the recess. The hole 16 receives a plunger 17 having a conical tip 18 and a shank 19 of somewhat reduced diameter. The larger end 10 of the plunger is slidably fitted in the hole 16 and substantially fills the same. A coiled spring 20 surrounds the reduced shank 19 and is positioned in the hole 16 back of the enlarged portion of the plunger 17.

A metal guide 21 of angular cross-section is secured to the end of the block that carries the plunger 17. One leg 21a of the angular guide 21 is secured in a vertical position to the end of the block that the plunger 17 is located in. The leg 21a is provided with an opening of substantially the same diameter as the reduced section 19 of the plunger 18. The opening is coaxially aligned with hole 16 and the plunger extends through that opening. The coiled spring 20 thus abuts the upright leg 21a of the guide 21 and is held in compressed position thereby so as to force the plunger in a direction toward the recess 13.

The horizontal leg 21b of the guide 21 is provided with a rectangular notch 22 receiving one arm of an angular lever or handle 23. That arm 30 of the lever is pivotally connected to the outer end of the plunger 17 and prevents the plunger from being forced completely out of the hole 16 into the recess 13 by the spring 20. The other arm 35 of the lever 23 is adapted to be engaged by the hand of the operator to retract the plunger 17. In retracting the plunger the lever is forced from its normal position, shown in dotted lines, to the full line position shown in Figure 1 and in so doing it fulcrums about the bottom of the notch 22 in the guide 21. When the lever is released the spring 20 returns the plunger and handle to the dotted line position in Figure 1.

Figures 3 and 4 illustrate one form of blade holder which is adapted to bevel the edges of a composition board or similar object. The blade holder comprises a block 31 of substantially the same shape as the recess 13. The block 31 has a V-shaped tongue 24 which fits within the angular groove 14 in one side of the recess 13. A pair of outwardly extending inclined shoulders 25 fit against the shoulders 15 at one side of the recess. At the end of the block 31 opposite the tongue 24 is a conical recess 26 adapted to receive the conical tip 18 of the plunger 17.

The block 31 is provided with a notch 27 (see Figure 6) extending in from one side thereof, the bottom of which is inclined. A cutting blade, which may be a common razor blade 28, is laid flat on the inclined surface with its cutting edge

extending below the bottom surface of the blade holder, as indicated in Figure 4. The blade is held in place by a cap 29 of any suitable material attached to the blade holder by a screw 30.

A suitable guide 32 of the shape shown in Figures 3, 4 and 5 is rigidly attached to the side of the blade holder adjacent the cutting blade. The guide 32 is notched out at 33 and the edges of the notch are beveled as at 34 to permit shavings to leave the notch 27 in the block 31 and prevent the tool from clogging. The guide extends a considerable distance below the bottom of the blade holder and below the bottom of the main body portion when the blade holder is in place. The guide is adapted to be positioned against an upright edge of a board to hold the cutting blade in proper position relative to the work as the tool is traversed along the work.

The blade holder is positioned in the body portion in the manner disclosed in Figure 5 with the guide 32 extending a substantial distance below the main body portion. The blade holder is placed in the body portion by retracting the plunger 17 and pushing the blade holder upwardly into the recess so that the tongue 24 and shoulders 25 engage the groove 14 and shoulders 15 on the body portion. The top surface of the blade holder, of course, fits flush against the top of the recess 13. The plunger is then released and the spring 20 forces the plunger 17 into the recess 26 in the end of the blade holder. The latter is thus securely latched in place.

Another form of blade holder and its cutting blade is shown in Figures 7 and 8. This blade holder is primarily for the purpose of severing a board of composition material or the like into two parts. The blade holder is composed of two identical blocks 41 and 42. The two blocks are secured together by means of transverse screws 43 and carry between them a razor blade or other cutting blade 44. Preferably the cutting blade is inclined as shown in Figure 7. The two blocks 41 and 42 when assembled together fit closely within the recess 13 in the body portion of the tool. The blocks are provided with tongues 45 which fit in the groove 14 and are also formed to provide a conical recess 46 to receive the tip of the plunger 17. This blade holder is positioned in and released from the body portion of the tool in the same manner as the previous device. It is not furnished with a guide, such as the guide 39, because the cutting blade is normally used at a considerable distance from an edge of the work and some other form of guide must be employed.

From the foregoing it will be seen that this invention provides a simple, convenient and economical tool for making various types of cuts in composition boards and the like. The variety of cutting blades and tool holders employed is practically unlimited, though only two have been shown for purposes of illustration. A wide variety of tools which take up little space and are relatively light in weight may be carried about and yet so rapidly interchanged with each other as to make them practically one tool. This eliminates the need for providing a number of relatively large and cumbersome tools for the different requirements.

The manner of locking the blade holders in the main body portion is positive in action yet provides for instant release of the blade holders when desired.

The scope of the invention is indicated in the appended claims.

I claim:

1. A cutting tool of the character described comprising a hand engaging body portion having a bottom work engaging surface and an upwardly extending recess therein, a unitary blade holder located in said recess and substantially filling the same, and releasable latch means on said body portion for releasably securing said blade holder in said recess.

10 2. A cutting tool of the character described comprising a hand engaging body portion having a work engaging bottom surface and a non-circular recess extending upwardly from said bottom surface, a unitary blade holder mounted in said recess, said blade holder being of substantially the same shape as said recess whereby to prevent turning movement of said blade holder in said recess, and releasable latch means on said body portion for releasably securing said blade holder in said recess.

15 3. A cutting tool of the character described comprising a hand engaging body portion having a work engaging bottom surface and a generally rectangular recess extending upwardly into said body portion from said bottom surface, a unitary blade holder positioned in said recess, said blade holder and the walls of said recess being formed to provide cooperating interlocking means preventing relative lateral movement of said blade holder and body portion, and releasable latching means on said body portion engaging said blade holder for preventing relative vertical movement of said blade holder and body portion.

20 4. A cutting tool of the character described comprising a hand engaging body portion having a work engaging bottom surface and a recess extending upwardly from said bottom surface, a unitary blade holder removably mounted in said recess, a cutting blade fixedly connected to said blade holder and removable therewith, said blade holder and body portion having cooperating interlocking means thereon for preventing lateral and longitudinal movement of said blade holder relative to said body portion, and releasable latch means on said body portion engaging said blade holder for releasably latching the latter in said recess.

25 5. A cutting tool of the character defined in claim 4 wherein said latch means comprises a spring pressed plunger slidable in said body portion and engageable in a recess in said blade holder.

30 6. A cutting tool of the character defined in claim 4 wherein said latching means comprises a spring pressed plunger slidable in said body portion and a lever pivotally attached to said plunger for retracting said plunger to release said blade holder.

35 7. A cutting tool of the character defined in claim 4 wherein said blade holder is provided with rigid guide means for engaging an edge of the work, said guide means extending at right angles to the bottom surface of the tool.

40 8. A cutting tool of the character described comprising a hand engaging body portion having a bottom work engaging surface and an upwardly extending non-circular recess therein, a unitary blade holder mounted in said recess, said blade holder being of substantially the same shape as said recess whereby to prevent turning movement of said blade holder in said recess, and means on said body portion for releasably securing said blade holder in said recess.
